PAPER PULP PLATE

Ernest Huff, Milwaukee, Wis., assignor to
American Lace Paper Company, Milwaukee,
Wis., a corporation of Wisconsin

Application October 24, 1931. Serial No. 570,781

4 Claims. (Cl. 229—2.5)

This invention relates to improvements in paper pulp plates.

It is the primary object of the invention to provide a novel and improved plate specially designed for manufacture from paper pulp and adapted to overcome objections previously made against paper pulp plates.

More specifically, it is my purpose to provide a paper pulp plate which is adapted to maintain its form and position when in use. Ordinarily plates made of paper pulp bend under the slightest load and slide so easily upon a table or like supporting surface as to make it difficult to use a knife and fork to cut food upon the plate.

15 It is a further object of the invention to provide a novel and improved plate design which is so developed as to facilitate handling and use of the plate notwithstanding the presence of a marginal flange for engaging and supporting the 20 plate from a table or the like.

In the drawing:

Figure 1 is a view in perspective of a paper pulp plate exemplifying this invention.

Figure 2 is an enlarged detail illustrating the 25 transverse cross section of the plate.

Like parts are identified by the same reference characters throughout the several views.

The plate is cast to provide integrally a bottom 3, an annular rim 4, and a marginal flange 5, 30 which is connected at its top with the rim and preferably is formed to extend substantially perpendicular with reference to the supporting surface represented by line 6 in Figure 2. In order that the plate may be grasped readily, portions 35 of the flange 5 are cut away on arcuate lines, leaving finger openings as shown at 7.

Following the casting operation by which the plate is formed it is preferably subjected to high pressure which leaves its surfaces hard and 40 smooth. If the bottom portion 3 of the plate constituted the sole means for engagement with the supporting surface 6 the plate would be subject to the usual difficulties in the way of distortion and slippage. Preferably, however, 45 the plate is so designed that its bottom portion 3 is slightly out of contact with the supporting surface but is sufficiently close thereto so that under pressure of food or of a knife and fork during a food-cutting operation, the bottom may 50 receive support from the table.

Following the completion of the pressure operation upon the plate it is necessary to trim the lower marginal edge of flange 5. At this time also the openings 7 may be cut therein if desired. It is important to note, however, that

whereas the fibers on all of the side, bottom and top faces of the component elements of the plate have been pressed and flattened, the trimming of the lower edge of flange 5 leaves the ends of the fibers exposed for engagement with the supporting surface.

Thus, not only due to the very small area of the lower edge of flange 5, but also due to the ends of the fibers exposed along said edge, there is a high resistance offered to any lateral movement of the plate upon its supporting surface, and as a result the plate may be used with just as much ease and comfort as any china dish affords.

Distortion is also avoided in the design shown due to the support for the margins of the plate, which is provided by flange 5. The construction is such that under any reasonable circumstances the plate will retain its form and hold its contents securely. Since the bottom 3 is out of contact with the supporting surface, and since the edge of flange 5 is trimmed to a given plane, any slight irregularities which may occur in manufacture will be rendered ineffective to disturb the equilibrium of the plate upon completion of the trimming operation.

The arcuate shape of the openings 7 distributes effectively all strains on the rim of the plate while permitting the fingers to rest naturally beneath the plate rim in handling the plate.

I claim:

1. As a new article of manufacture, a plate of pulp having a bottom, a rim, and an annular marginal flange with pressure hardened surfaces, the lower edge of said flange having the ends of its pulp fibers exposed at a level such as to engage a table surface for the support of the plate against lateral displacement.

2. A plate having a bottom, an upwardly inclined annular rim, and an annular flange substantially vertical in cross section, said bottom, rim and flange being integrally formed of pulp, and said flange being extended slightly below the plane of said bottom and being provided with a plurality of openings through which the fingers of an operator may be passed to engage said rim and with a trimmed edge exposing cut fiber ends whereby to resist displacement of the plate on a supporting surface.

3. A plate having a bottom, an upwardly inclined annular rim, and an annular flange substantially vertical in cross section integrally formed of pulp, said flange being extended slightly below the plane of said bottom and being provided with a plurality of openings through which the fingers of an operator may be passed to en-

gage said rim, the surfaces of said bottom and rim comprising pressure hardened pulp fiber and the lower edge of said flange exposing the severed ends of fibers for engagement with a supporting surface.

4. A pulp receptacle having pressure hardened exposed surfaces and a trimmed supporting flange

of which the marginal edge is positioned to comprise the support of said receptacle and upon the supporting edge of which the cut ends of pulp fibers are exposed, whereby to resist lateral displacement on a supporting surface.
